UNITED STATES PATENT OFFICE.

PHILANDER KILE TUCKER, OF SIOUX FALLS, SOUTH DAKOTA, ASSIGNOR OF ONE-HALF
TO MIKE HENGEL, OF SIOUX FALLS, SOUTH DAKOTA.

INNER-TUBE PROTECTOR.

1,294,201.

Specification of Letters Patent.

Patented Feb. 11, 1919.

Application filed July 27, 1918. Serial No. 247,048.

To all whom it may concern:

Be it known that I, PHILANDER KILE TUCKER, citizen of the United States, residing at Sioux Falls, in the county of Minnehaha and State of South Dakota, have invented certain new and useful Improvements in Inner-Tube Protectors, of which the following is a specification.

This invention relates to certain new and useful improvements in an inner tube protector and it has for a principal object to provide a metallic armor consisting of a series of flexible overlapping plates for insertion between the casing and the inner tube of an automobile tire to protect the tube against puncture.

The invention further resides in an improved form of plate having means for detachably connecting the same to the adjacent plate in a secure and locked manner.

Further, the invention resides in the features of construction and the arrangements and combination of parts hereinafter described and claimed, reference being had to the accompanying drawing wherein:

Figure 1 is a fragmentary side elevation of a wheel, the tire being broken away to show the application of the protector;

Fig. 2 is a transverse section thereof on line 2-2 of Fig. 1;

Fig. 3 is a bottom plan view of a fragment of the protector, more clearly illustrating the connection between the plates;

Fig. 4 is a central longitudinal section thereof; and

Fig. 5 is a view illustrating the manner of connecting and disconnecting the plates.

Referring more in detail to the drawing, the casing 1 and inner tube 2 are interposed by the protector consisting of a plurality of flexible overlapping plates 3 of thin tempered steel, and a means of connection therebetween.

This means of connection consists of a tongue 4 formed on one side edge of each plate 3 at a substantially central point, said tongue having a head and a reduced neck part 5 which supports the head spaced from the side edge of the plate and defines a short slot 6 on one side and a long slot 7 on the other, the inner end wall 8 of the latter inclining inwardly in a downward manner toward the base of the neck. The head thus extends farther on one side than on the other, and the outer edge of the

head is preferably semi-circular. Beneath the tongue and in the body of the plate is provided a transverse slot 9 of a length less than the width of the head of the tongue.

In connecting the plates into band formation, the tongue of one plate is tilted for inserting the point 10 initially through the slot 9 of the adjacent plate and then shifted laterally to the right to bring the edge of the slot into the longer tongue slot 7. With the edge of the plate slot located at the inner lower end of the inclined wall 8 the opposite point 11 is permitted to pass through the slot 9 so that the tongue and plate may now be shifted to the left. This leftward shifting brings the opposite end of the slot 9 into the shorter slot 6 in which position the first end of the slot 9 will be located at the upper outer end of the wall 8. From Fig. 3, it will be noted that the semi-circular edge of each tongue extends over the neck portion of the tongue of the adjacent plate and over the inner end of the slot 7 to close the same and since, in unlocking a section, it is requisite to dis- pose one end of a slot 9 in the innermost corner of tongue slot 7 in order to permit passage of the opposite corner 11 of the tongue through the opposite end of the slot 9, said overlapping semi-circular edge will lock a third plate against removal. In order that the rounded outer or free end of the tongues may be retained operative across the inner end of the slots 7, said free ends are inserted through the transverse plate slot 9 of the third plate, and to unlock or remove a plate it is necessary to first remove the free end of a tongue from its second engaged plate slot whereupon the inner end of the predetermined slot 7 will be uncovered for receiving the adjacent end of a plate slot 9. When thus positioned, the point 11 of the head is swung downwardly through said plate slot and the head entirely withdrawn.

Thus, the head can not be removed except by first passing the point 11 through the plate slot, and such point is only positioned for removal when the opposite end of the plate slot is located at the lower inner end of the slot 7. This latter is only obtainable when the said inner end is uncovered by an overlapping tongue.

It will therefore be clear that the overlapping tongues securely and positively lock

the heads against accidental displacement. The overlapping tongues occur at the center of the flexible protector band thereby doubly reinforcing the tread of the tire. The plates are preferably tapered toward the sides of the tire and overlap throughout their lengths. They may expeditiously be stamped from thin steel sheets. Being flexible the plates readily yield and conform to the shape of the tire, and being connected only at their centers the ends of the chain of plates will slide over each other to increase their overlap.

What is claimed is:

15 1. A protector for tires comprising a plurality of overlapping plates each having a slot and a tongue extending from one edge of the plate for interlocking in the slot of an adjacent plate, said tongue having a reduced neck of less width than the length of the slot to permit shifting of the neck into one end of the slot whereby the opposite side of the tongue may be passed through the slot on relative angular movement between the connected plates, and means supplementing the width of the neck to lock the neck against shifting in the slot.

20 2. A protector for tires comprising a plurality of overlapping plates each having a slot and a tongue extending from one edge of the plate for interlocking in the slot of an adjacent plate, said tongue having a reduced neck of less width than the length of the slot to permit shifting of the neck into one end of the slot whereby the opposite side of the tongue may be passed through the slot on relative angular movement between the connected plates, the tongue of a third plate which passes through the slot of said 25 adjacent plate having its outer end extending over the neck of the first tongue to increase its width and thereby prevent removal of said first tongue.

30 3. A protector for tires comprising a plurality of overlapping, thin, tempered, steel plates arranged transversely of the tire and provided with centrally located tongues each tongue having a short slot extending in from one edge thereof and a long slot extending in from the opposite edge thereby defining a head part and a neck part, the inner end wall of the long slot inclining inwardly to-

ward the base of the neck and adapted to be covered by the head of an adjacent tongue, said plates provided with slots for receiving the tongues.

4. A protector for tires comprising a plurality of overlapping interlocked plates each having a slot in its body and a part extending from one edge of the plate for interlocking in the slot of an adjacent plate, said part undercut from opposite sides by inwardly extending slots, the length of the slot being in excess to the distance from the inner end of one undercutting slot to the opposite side edge of said part whereby the latter may be removed from the body slot, and means extending across the inner end of the specified undercutting slot for locking the tongue against removal.

5. A protector formed of a plurality of overlapping flexible plates each formed with a slot and a tongue interlocking with a slot of an adjacent plate, each tongue having a lateral cut out defining a head and permitting the insertion and removal of the head in a slot, said tongues furthermore overlapping the cut outs of adjacent tongues to lock the same against removal.

6. A protector for tires comprising a plurality of overlapping interlocked plates each having a slot in its body and a part extending from one edge of the plate for interlocking in the slot of an adjacent plate, said part undercut from opposite sides by inwardly extending slots, the length of the slot being in excess to the distance from the inner end of one undercutting slot to the opposite side edge of said part whereby the latter may be removed from the body slot, and means carried by a third plate and extending across the inner end of the specified undercutting slot for locking the tongue against removal.

7. A protector formed of a plurality of overlapping flexible plates each formed with a slot and a tongue interlockable with the slot through a relative pivotal movement, said tongues having their extreme ends engaging the slots of the second adjacent plates for overlapping and locking the tongues respectively engaged therein.

In testimony wherof I affix my signature.

PHILANDER KILE TUCKER.
